PLAYER-PIANO.

1,391,376.

Specification of Letters Patent. Patented Sept. 20, 1921.

Application filed April 24, 1918. Serial No. 230,417.

To all whom it may concern:

Be it known that I, STANLEY L. FISHER, a subject of the King of Great Britain, residing in Chester, county of Middlesex, State 5 of Connecticut, have invented certain new and useful Improvements in Player-Pianos, of which the following is a full, clear, and exact description.

This invention relates to piano players 10 and it has more particular reference to pneumatically actuated pianos of the upright type, wherein a so-called "upper action" or chest with its appurtenant valve mechanism and pneumatics for operating the respective 15 units of the piano action proper, extends across the front of the piano in the case thereof above the key-board and in front of the piano action, each unit of the player action being properly connected with and 20 adapted to operate the corresponding unit of the piano action. Each piano action unit ordinarily comprises a hammer for striking the string, a pivoted wippen or jack beam, and a hammer jack mounted on the wippen 25 in the customary manner, the wippen being operated to actuate the hammer by a connection with the corresponding player action unit for pneumatic playing, and said wippen being connected with the correspond- 30 ing key of the piano for playing by hand.

One of the primary objects of my invention is the provision of an improved and simplified player action of the type set forth, which has the advantages of simplicity, compactness, efficiency of operation, ready accessibility for inspection and repairs, and low cost.

Another object of my invention is to furnish a simple, compact chest work, in which 40 the valves are disposed toward the front of the piano and so located that access can be had to them with maximum facility and with the removal of a minimum number of parts. By the construction hereinafter described, it is possible to locate a faulty valve with great readiness and convenience and the same can then be very quickly repaired or replaced, or the valve and its adjacent passages can be very easily and quickly 45 cleaned if the fault arises solely from the lodgment of dust or lint on the valve or its adjacent parts.

Another object is to provide a construction

in which the valves can be removed bodily from the chest after taking off a cap plate 55 or the like, which is preferably divided for convenience into a number of sections, each removable independently of the others. Thus, when difficulty with any particular valve is encountered, the corresponding cap 60 plate section is taken off, the same being readily accessible at the front of the action as soon as the upper panel of the piano case is removed, and when the cap plate is taken off, the valve can be freely lifted off of its 65 seat for inspection, cleaning or repairs, as above stated. The valve mechanism is thus made very accessible and it can be kept in good working order with a maximum of convenience.

Another object of the invention is to provide a construction in which the valves seat themselves surely and accurately when the instrument is being played, so that the notes are properly struck, and, as a quick, positive 75 cut-off is insured by the valves, perfect repetition can be obtained.

Another advantage which I have in view is that all the valves appurtenant to two or more tiers of striker pneumatics shall be 80 located in a single chest above the level of the pneumatics, where they will be substantially uniformly accessible, preferably from the front of the piano, said valves being removable from the action without disturbing 85 the striker pneumatics in any way.

Still another object of the invention is to provide an improved form of connection between the striker pneumatics and the corresponding units of the piano action. By 90 my improvements, the number of parts interposed between each pneumatic and the corresponding piano action unit is cut down to a minimum, and yet provision is made for easy and nice adjustment of the parts, which 95 can be readily carried out when the player action is installed in the piano case, so that the hammers will strike the strings uniformly.

To these and other ends, the invention 100 consists in the novel features and combinations of parts to be hereinafter described and claimed.

In the accompanying drawings:

Figure 1 is a diagrammatic, vertical trans- 105 verse section through the upper portion of a

player piano embodying my improvements, showing the main parts of one of the piano action units and the wind chest, valve mechanism and striker pneumatics of the player 5 action;

Fig. 2 is an enlarged front view of a portion of the pneumatic action with the muffler or valve cover removed, showing the cap plate and valves in position;

Fig. 2^A is a front elevation of one end portion of the wind chest, with the muffler, cap plate and valves removed, showing the chest block and the valve seats therein;

Fig. 3 is a rear elevation of one end portion of the pneumatic action as the same would appear detached from the piano;

Fig. 4 is a top plan view of the pneumatic action detached and partly broken away;

Fig. 5 is a bottom view of a part of the 20 pneumatic player action;

Fig. 6 is a detail section on a somewhat smaller scale, taken on line 6—6 of Fig. 1;

Fig. 7 is a detail section of one of the valves and its actuating dowel or bumper;

Fig. 8 is an end view of the dowel or bumper;

Fig. 9 is a rear view of the chest block with the diaphragm board removed; and

Fig. 10 is an inner face view of a portion 30 of the diaphragm board.

In the practice of my invention, the piano action A can be, for the most part, of the usual type, although various changes may be made in this respect. In the embodiment 35 illustrated, I have shown the ordinary form of piano action unit, comprising a hammer 10 for striking the string 11, pivoted at 12 to the rail 13, from which is pivotally supported at 14 the customary wippen 15, carrying the usual pivoted hammer jack 16 and other parts which I have not considered it necessary to illustrate. Pivoted to the wippen 15 near the outer end thereof at 17 is the customary sticker or abstract 18. All 40 of these parts, as shown, are of the usual construction.

Extending across the front of the piano, in front of the piano action, above the keyboard (not shown) is a pneumatic player action, designated by reference character B. This pneumatic action B, or more accurately this upper player action—there being a so-called lower action (not shown) comprising pedal operated exhausting apparatus, etc., located beneath the key-board—comprises a wind chest 19 connected at one end by the duct 20 with the pressure reducing apparatus, a plurality of striker pneumatics 21, 22, for actuating the respective 50 units of the piano action A, and a plurality of valves 23 in the wind chest for controlling the operation of the pneumatics. The valves 23 are controlled from the usual tracker bar 24, illustrated diagrammatically in Fig. 60 1, the openings of the tracker bar being con-

nected by means of tubes 26 and suitable passages with the chambered diaphragm board 27 at the rear part of the wind chest.

Referring now to the detail construction 70 of the chestwork, it will be observed that

the chest or chamber 19, running lengthwise of the action, is formed in an elongated block 28 which is open at the rear but closed by the diaphragm board 27 when the latter is placed in position, the diaphragm 75 board being secured in an air-tight manner to the block 28 and also to a block 29 superposed on block 28 and having a bleed passage 30 with which the tracker tubes communicate, as hereinafter described. At the 80 front of the chest block 29, the same is bored out horizontally, as shown at 31, to provide a plurality of chambers accommodating the valves 23, the valves and valve chambers being arranged in two rows in 85

the present instance, corresponding to the two rows or tiers of striker pneumatics 21, 22. Projecting rearwardly in the wind chest, in line with the respective rows of valve chambers, are shelves 32, in which are 90 slidably mounted the stems 33 of valve actuating dowels or bumpers 34. Referring to Fig. 7, it will be seen that each valve 23, which is a double valve, is slidably mounted on one end of the bumper stem 33, whereas 95

a bumper head 35 is rigidly secured to the other end of the stem by screw threads 36 or the like. At the back of each of the bores or valve chambers 31, a smaller bore extends from the valve chamber to the interior of 100 the chest, said bore communicating with the chest, in this instance, both above and below the corresponding shelf 32, as shown more particularly in Figs. 1 and 9. A bushing 37 is driven into this bore from the front, 105 so as to form a valve seat at the rear part of the corresponding valve chamber. Coöperating with this seat is the rear part 23^a of the double valve 23, which valve may be conveniently made of two wooden parts in 110 telescopic relation, glued together, as shown in Fig. 7, the rear part 23^a having a stem 23^b loosely fitting over the bumper stem 33. The front part of the double valve, which is designated 23^c, is slipped over the stem 23^b and glued thereto, and it coöperates with 115 a seat on a cap plate 38 suitably fastened to the front of the chest block, as shown in Fig. 2. The cap plate 38 is constituted by a comparatively thin strip of wood having openings 39 which register with the valves 23, and the front parts 23^c of the valves are adapted to make air-tight contact with the rear surface of the cap plate around the 120 openings 39. The cap plate 38 is, in turn, 125 covered by a muffler 40, so that when the apparatus is in use the valves and valve openings are concealed, but it will be understood that the outer parts of the valve openings 39 are, nevertheless, in free communication 130

with the atmosphere at all times, so that when the part 23^c of a valve is moved away from the corresponding valve seat on the cap plate, atmospheric air can enter the valve chamber. Air so entering one of the upper valve chambers 31 of the chest block, passes downward through a vertical passage 41 to one of the pneumatics 21 of the upper tier, and similarly, air entering one of the lower 10 valve chambers passes downward through a passage 42 to one of the pneumatics 22 of the lower tier.

The vertical passages 41, 42 are formed partly in the chest block 28 and partly in 15 a board or strip 43, into which said passages enter at the upper edge of said board, which upper edge is glued or otherwise suitably fastened to the under surface of the chest block. Glued or otherwise suitably fastened to the lower surface of the chest block at the back of the board 43 is a connecting strip or rail 44, and a lateral passage 45 formed partly in the rail 44 and partly in board 43 communicates with the 20 lower end of the vertical passage 41 at the forward end of passage 45. At the rear end of the passage 45, the same is deflected downwardly, so as to communicate through an opening 46 with the interior of the corresponding 25 striker pneumatic 21. This pneumatic 21 and its fellows of the upper tier have their upper fixed parts or leaves glued or otherwise suitably fastened to the connecting rail 44, and it will be understood that each of said pneumatics communicates 30 with one of the upper valve chambers 31 by passages 45, 41, substantially as herein described. The pneumatics 22 of the lower tier are similarly applied to a rail 47, similar to the rail 44, said rail 47 being glued or otherwise suitably secured edgewise to the 35 rear surface of the board 43 beneath the upper pneumatics and being provided with a plurality of lateral passages 48 (shown in dotted lines in Fig. 1) which communicate at their forward ends with the vertical 40 passages 42 leading to the lower valves, whereas the rear ends of said passages 48 communicate with the interior of the respective 45 pneumatics 22 of the lower series. The under surfaces of the connecting rails 44, 47 are upwardly beveled, so that the corresponding tiers of pneumatics applied thereto are given a rearward and upward inclination, as shown in Fig. 1, although this is not necessary in all cases. The diaphragm board 27 is provided at its inner face with a plurality of diaphragm chambers 49, which, like the valve chambers and the 50 pneumatics, are arranged in staggered relation in two rows. Each diaphragm chamber is covered at the front by a diaphragm 55 of the usual material, lying in substantial contact with the head 35 of the adjacent 55 valve bumper 34 and adapted to actuate the

valve by means of said bumper. Each diaphragm chamber is in communication with a vertical passage or duct 51 in the diaphragm board, leading by way of ducts 52, 53 to one of the tracker tubes 26. Each 70 tracker tube is connected to the corresponding duct 53 by an elbow 26^a. At the junction of the ducts 52, 53, a bleed 54 is provided, affording restricted communication with the longitudinal passages 30 in block 75 29, which longitudinal passage is in communication with the exhausting apparatus, through connections, not shown, and well-known in the art.

The pneumatics 21, 22 are collapsed by 80 the admission of air to the action through the perforations in the music sheet and the holes in the tracker bar, in a manner more particularly described hereinafter. As the pneumatics collapse, their lower, movable 85 parts or leaves are raised, and this movement is transmitted to the corresponding units of the piano action A, in such a manner that the strings are properly struck by the hammers. For this purpose, each of the stickers 90 or abstracts 18 of the piano action is adapted to be actuated by a rigid striker on the corresponding pneumatic. Each of the upper pneumatics, in the form shown, has a small, rigid striker constituted by a cleat 55 rigidly 95 secured by a screw 56 to the under surface of the movable leaf of the pneumatic at the rear of said leaf. A part of the cleat extends rearwardly beyond the leaf and under a button 57 carried by a bracket 58 that is 100 rigidly secured by a screw 59 or the like to the front edge of the corresponding sticker 18. The button 57 has a layer of felt 57^a on its lower surface, adapted to be struck by a striker or cleat 55. The normal position 105 of the parts is shown in Fig. 1, from which it will be evident that as the upper pneumatic 21 is collapsed, the button 57 (and bracket rigidly secured thereto) will be raised, thereby carrying upward the sticker 110 18 to a sufficient extent to operate the hammer 10. The brackets 58 appurtenant to the pneumatics 22 of the lower tier are arranged in line with those appurtenant to the upper pneumatics, and the lower pneumatics 115 are provided with rigid strikers which extend up into co-operation with the corresponding brackets 58, it being understood that by preference the single line of brackets will extend across the piano action approximately in line with the pneumatics of the upper tier, as shown, although changes may be made in this regard. The rigid strikers of the lower pneumatics 22 are formed by cleats 55^a secured to the lower leaves of said 120 pneumatics by screws 56 in substantially the same relation as the cleats 55, but the cleats 55^a are provided with rigid upward extensions 55^b, located adjacent the rear ends of pneumatics 22 and presenting rigid finger- 125 130

like members which extend at their upper ends into the spaces between the cleats or strikers 55 with which they alternate. The strikers of both the upper and lower tiers 5 are preferably made of wood, and their upper striking surfaces, coöperating with the buttons 57, are preferably slightly curved, so as to make the most advantageous striking contact with the buttons on the brackets 10 58. The buttons 57 are vertically adjustable, inasmuch as they are provided with threaded stems or shanks 57^b engaging threads in the respective wooden brackets. At their upper ends, the threaded shanks are 15 provided with manipulating heads 57^c, which enable them to be screwed up or down *i. e.* toward or away from the coöperating rigid strikers 55 or 55^b. In this manner, a 20 very nice adjustment of the player action can be obtained after the same has been installed in the piano case, and all lost motion 25 between the pneumatics and the corresponding strikers can be readily taken up, so that a fully effective actuation of the piano action unit by the corresponding player action unit 30 will be insured. On the other hand, in order to prevent an upward movement of the sticker beyond the extent required, a suitable stop mechanism is provided. Preferably, 35 this stop mechanism coöperates with the brackets 58 or parts thereof, and is in the form of a rail having a plurality of independently adjustable stop members. In the example shown, a stop rail 60 extends 40 across the upper faces of the pneumatics 21 of the upper tier at the rear of said pneumatics and lengthwise of the piano. The rail 60 may be supported by brackets 61 at the ends of the player action, as shown 45 in Fig. 4, said brackets extending alongside the end pneumatics of the upper tier in parallel relation thereto and having their rear ends underlying the rail 60 and secured thereto by screws 62. At their forward 50 ends, the supporting brackets are preferably interposed and secured between the connecting rails 44, 47. The rail 60 carries a plurality of stops 63, preferably constituted by buttons similar to the buttons 57, having 55 threaded shanks 63^a engaging screw threaded openings in the stop rail and provided at their upper ends with manipulating heads 63^c. The rear part of the stop rail projects 60 beyond the upper pneumatics, so as to overhang the same, and stops 63 are supported by the overhanging portion of the rail with the buttons below the stop rail and the manipulating heads 63^b above the same, where they are readily accessible. The brackets 58 65 on the stickers are preferably substantially L-shaped, the upper leg being attached to the sticker by the screw 59 and the lower leg carrying the adjustable striker contacting button 57. The lower leg of the bracket 65 is preferably beveled at its upper face in a

direction rearwardly and upwardly toward the sticker, and the corresponding stop button 63 on the stop rail is arranged in opposing relation, so that its lower felted surface 63^c is parallel to and opposes the beveled 70 surface on the bracket slightly in front of the threaded stem 57^b. When the corresponding pneumatic is collapsed, the sticker is raised until the beveled surface of the 75 bracket engages the under surface of the stop button, which can be adjusted by manipulation of the shank 63^a, so that the upward movement of the sticker is arrested at exactly the proper point.

It will be understood that by arranging all 80 of the brackets 58 in one row, a single stop rail will suffice for limiting the movement of all the various piano action units actuated by the pneumatic player action, by reason of the coöperation of the stop rail with all of 85 the brackets. Nevertheless, the striker mechanism, on the other hand, or, in other words, the means for striking the bracket, is of the very simplest construction, because the cleats rigidly applied to the upper pneumatics are of the simplest form and of very small size, while the cleats of the pneumatics of the lower series merely have to be equipped with a relatively small upper extension which, in the process of manufacture, can be readily applied to or formed integral with the main part of the cleat attached to the movable leaf. The brackets 58 will, of course, be attached to the stickers 95 at the most convenient height, and the 100 player action is thereby adapted to pianos of different heights.

The operation of the pneumatics by means of the pressure exhausting apparatus controlled from the note sheet will be more or 105 less obvious from the foregoing description. When the pumps of the instrument are working, the tracker tubes 26 are exhausted so long as they do not register with openings of the music sheet, by virtue of the suction produced in the bleed passage 30. Consequently, the diaphragms or pouches 50 are deflated and the valves 23 tightly seat on the metal bushings or seats 37. This cuts off communication between the wind chest 20 and 110 the valve chambers 31, and, at the same time, establishes communication between said valve chambers and the atmosphere, owing to the fact that the parts 23^c of the valves 23 stand off their seats in the cap plate 38, 115 enabling air to pass from the atmosphere through the ports 39 into the valve chambers and thence into the pneumatics, which remain in the normal inflated condition. When one of the openings of the note sheet 120 passes over the corresponding tracker bar opening, the appurtenant tracker tube 26 is opened to the atmosphere, destroying the vacuum in the diaphragm chamber and causing the diaphragm to shift the valve 23 125 130

to the left by means of the valve operating dowel or bumper 34. The part 23^c of the valve is thus pushed against its seat on the cap plate, cutting off communication with the atmospheric air, and simultaneously the part 23^a of the valve is moved off of the seat 37, establishing communication between the corresponding pneumatic and the exhaust through the valve chamber and the 10 passages 41, 45 or 42, 48 as the case may be. When the pneumatic is placed in communication with the wind chest, it is collapsed and the corresponding piano action unit is actuated in the manner previously described.

15 As soon as the perforation in the music sheet comes to an end and the sheet closes the hole in the tracker bar, the air between the diaphragm and tracker bar is immediately exhausted through the bleed 54, and the valve 20 23, now relieved of the pressure of the diaphragm 50, is forced back on its seat 37 by the pressure of the outside air on the outer part or disk 23^c. Thus, the communication of the pneumatic with the outside air is 25 again restored simultaneously with the cutting off of the pneumatic from the wind chest and pumps.

It will be understood that the valves 23 have a certain amount of free movement on 30 the forward ends of the bumper stems 33, owing to the fact that the bores in the valves are somewhat larger than the diameter of said stems. When the bumper shifts the valve against the seat on the cap plate, the 35 front end of the stem 33 engages the bottom of the bore in the valve, as will be manifest. The loose fit of the valve on the bumper stem provides, however, for a certain amount of movement of the valve independently of the stem and prevents binding, thus causing the valve to seat accurately and surely both against the cap plate and against the metal valve seat 37. In this manner, a quick and effective cut-off is produced and the repetition effects produced by the instrument are most satisfactory. Aside from the advantage just spoken of, the free mounting of the valves on the ends of the bumper stems enables the valves to be removed from the action independently of the bumpers. When the action of the player is faulty by reason of dust or lint entering the same through the tracker bar and lodging in the chest, the muffler 40 and 50 cap plate 38 can be readily taken off by removing a few screws, as said parts are located at the front of the action, where they are very readily accessible. When the muffler is removed, all the valves can be seen and the instrument can be played while the valves are visible, so as to determine which, if any, are not working properly. If a faulty valve is discovered, it can be readily taken out by removing that section

of the cap plate 38 appurtenant thereto. 65 When one of the sections of the cap plate is removed, all the valves beneath it are completely accessible and can be lifted out of their valve chambers if desired. In the case of a faulty valve, the same can be removed 70 for cleaning or for the substitution of another valve or for the cleaning of the valve chamber and adjacent passages, which are made quite accessible by the removal of the cap plate. 75

One of the advantages of my improved player action is that it can be very readily adapted to various pianos. In different pianos, the piano action units are differently spaced and grouped, and a player action 80 having pneumatics arranged to coöperate with the units of one piano will, in most cases, not coöperate properly with a piano action of a different make. In accordance with my invention, the greater part of the 85 chest work can be used with all kinds of pianos and can be manufactured in quantity and kept in stock. The only parts which need to be especially adapted to the piano in which the device is to be installed, are the 90 connecting rails 44, 47, the transverse passages of which have to be bored in such a manner as to locate the pneumatics at the proper point, and the stops 63 which must be spaced along the stop rail 60 to conform to 95 the action scale of the piano in which they are used. When the spacing of the piano action units is known, the connecting rails can be readily bored out in a simple manner to provide the necessary connecting passages 45, 48, which usually radiate from one or more centers, as shown in Fig. 6. The bores formed in the board 43 to constitute parts of the vertical passages 41, 42, with the lateral bores forming parts of the passages 100 45, 48, form what is known in the trade as the player action scale openings, while the openings at the rear ends of the passages 45, 48, in the connecting rails 44, 47, form what is known in the trade as the piano 105 action scale openings, these parts of the passages 45, 48 located in the connecting rails being bored out at the proper angle only when the spacing and arrangement of the piano action scale is known. It will be observed that the borings in the connecting rails are very simple and easy to make, and this applies also to the other borings and to 110 the pneumatic action as a whole. 115

The bleed passage 30, associated with the 120 upper block 29 of the chest work, has a detachable cover plate 30^a, so that access can be had to the several bleeds 54 when it is desired to clean the same.

The muffler 40 is secured in place by 125 screws extending into the cap plate 38. Atmospheric air is admitted to the valve ports in any suitable manner, as by leaving the

muffler 40 open at the ends. Changes in minor features of this character will suggest themselves to those skilled in the art.

It will be observed that the passages 41, 45 5 form in conjunction substantially L-shaped conduits, which connect the upper valve chambers in a very simple and direct manner with the upper pneumatics. The passages 42, 48 form similar L-shaped conduits, 10 which connect the lower valve chambers in a very direct manner with the pneumatics of the lower tier. The player action is made very compact by securing the connecting rails 44, 47 to the downward extension 43 15 at the front of the chest, so that said rails are located beneath the chest proper, in the angle between the latter and the downward extension. The upper connecting rail abuts at its upper surface against the lower surface 20 of the chest block, so as to be held in place against the chest block as well as against the board or downward extension 43 in the angle previously mentioned; and the lower connecting rail 47 is only slightly below 25 the upper rail. The compactness of the structure is also increased by inclining the pneumatics 21, 22 upwardly and rearwardly to a certain extent, as previously described. By giving the lower surface of each connecting rail an upwardly and rearwardly directed bevel or chamfer, the bulk of the rail is reduced and the passage connecting the pneumatic with the corresponding valve chamber is shortened, so that communication 30 is made more direct.

The cap plate is independent of the valves and it is not even necessary to provide it with means for supporting or guiding the valves, inasmuch as the latter are effectively 40 supported and guided on the bumper stems. When the cap plate is removed, the valves remain in place. The particular valve or valves which need attention can thereafter be readily pulled out of the corresponding 45 chamber or chambers. The diaphragm board has a similar relation to the valve bumpers, inasmuch as it is independent of the same, and because the bumpers are left in place when the diaphragm board is removed. After the removal of the diaphragm board, one or more of the bumpers can be 50 lifted out of the chest from the rear, as desired.

I do not claim in this application the novel 55 features of the mechanism for transmitting the motion of the movable leaf of the striker pneumatic to the piano action, nor do I claim herein the novel arrangement of the stop rail to limit the movement of the piano action, all of which forms the subject matter 60 of my divisional application, Serial No. 315, 208, filed August 4, 1919.

Various changes may be made in the details of the construction without departing

from the scope of my invention as defined in 65 the claims.

What I claim is:

1. In a pneumatic player action, a wind chest having valve chambers in the front part of the same connected by ports with 70 the main tension chamber and atmosphere, double valves in said valve chambers to control said ports, a cap plate applied to the front of the chest and provided with valve ports for coöperation with one or more of 75 said valves but mounted independently of the same, separate horizontally movable actuators for said valves in said chest, said chest being provided at the rear with dia- 80 phragm chambers, diaphragms in the dia- phragm chambers for operating said actuators, the latter being arranged to support and guide the corresponding valves, and pneumatics beneath the chest in communication with said valve chambers. 85

2. In a pneumatic player action, a wind chest having a tension chamber and a plurality of valve chambers at the front of the chest arranged in tiers, horizontally movable valves in said valve chambers, pneumatics beneath said chest having fixed upper leaves and movable lower leaves, said pneumatics also arranged in tiers, said chest having interior substantially L-shaped conduits connecting said valve chambers directly with 90 said pneumatics. 95

3. In a pneumatic player action, a wind chest having a main tension chamber and a plurality of valve chambers arranged in tiers at the front of said chest and communicating with said tension chamber, horizontally movable valves in said valve chambers, a plurality of pneumatics beneath the chest having fixed upper leaves and movable lower leaves, said pneumatics arranged in 100 tiers, connecting rails for said pneumatics having substantially horizontal passages leading to said pneumatics and upright passages leading from the last named passages directly to the valve chambers. 110

4. In a pneumatic player action, a wind chest having a main tension chamber and valve chambers, horizontally movable valves in said valve chambers, a downwardly projecting extension on said wind chest beneath said valves, and pneumatics communicating with said valve chambers through passages in said extension, and secured within the angle formed by the wind chest proper and the downwardly projecting extension thereof. 115

5. In a pneumatic player action, a wind chest having a downwardly projecting extension, horizontally movable valves in said wind chest, and pneumatics controlled by 120 said valves through passages in said extension, said pneumatics being secured to the chest within the angle between the main 125

part of the chest and said downwardly projecting extension.

6. In a pneumatic player action, a wind chest having a downwardly projecting extension, horizontally movable valves in said wind chest located substantially in vertical alinement with said extension, pneumatics secured to said extension, and substantially L-shaped conduits leading through said extension from the valves to the pneumatics.

7. In a pneumatic player action, a wind chest having a downwardly projecting extension, horizontally movable valves in said wind chest located substantially in vertical alinement with said extension, pneumatics secured to said extension, and substantially vertical communicating passages in the chest proper and extension, beneath said valves, in communication with said pneumatics.

8. In a pneumatic player action, a wind chest having a main tension chamber and valve chambers at the front of the chest, horizontally movable valves in said valve chambers, a downwardly projecting extension on the chest at the front of the same, substantially in vertical alinement with the valve chambers, and having passages communicating therewith, and pneumatics secured to said extension at the rear thereof and in communication with said first named passages.

9. In a pneumatic player action, a wind chest having a main tension chamber, and a plurality of valve chambers at the front of the chest, horizontally movable valves in said valve chambers, a downwardly projecting extension on the chest at the front thereof substantially in line with said valve chambers, and having upright passages communicating with said valve chambers, pneumatics at the rear of said extension beneath the main part of the chest, and a connecting rail for said pneumatics having substantially horizontal passages communicating with said first named passages.

10. In a pneumatic player action, a wind chest cut out at the rear portion thereof to present a main tension chamber, and provided at the front of said main tension chamber with a plurality of valve chambers, horizontally movable valves in said chambers, actuators for said valves at the rear of the chest, a cap plate applied to the chest at the front thereof and provided with valve ports and coöperating with said valves, a diaphragm board applied to the rear of the chest and provided with diaphragms for said actuators, a downwardly projecting extension at the front of the chest provided with passages, said chest being provided with upright passages connecting said first named passages with the valve chambers, a connecting rail applied to the lower part of the chest in the angle between the same and said

extension and having passages communicating with said first named passages, and pneumatics on said connecting rail in communication with said last named passages.

11. In a pneumatic player action, a wind chest cut out at the rear portion thereof to present a main tension chamber, and provided at the front of said main tension chamber with a plurality of valve chambers, horizontally movable valves in said chambers, actuators for said valves at the rear of the chest, a cap plate applied to the chest at the front thereof and provided with valve ports and coöperating with said valves, a diaphragm board applied to the rear of the chest and provided with diaphragms for said actuators, a downwardly projecting extension at the front of the chest provided with passages, said chest being provided with upright passages connecting said first named passages with the valve chambers, a connecting rail applied to the lower part of the chest in the angle between the same and said extension and having passages communicating with said first named passages, and pneumatics on said connecting rail in communication with said last named passages, the passages in the chest, extension and rail forming substantially L-shaped conduits connecting the valve chambers directly with the pneumatics.

12. In a pneumatic player action, a wind chest having a main tension chamber, said chest being provided at one side with a plurality of valve chambers communicating with said tension chamber, horizontally movable valves in said valve chambers, horizontally movable actuators for the valves in said chest, having operating heads located at the opposite side of the chest, a diaphragm board applied to the last named side of the chest and provided with diaphragms to operate said actuators, a cap plate applied to the other side of the chest and provided with valve ports to coöperate with said valves, a downwardly projecting extension on the chest, substantially beneath the valve chambers and having passages communicating therewith, a connecting rail in the angle between extension and chest proper having passages communicating with said first named passages, and pneumatics applied to said rail and communicating with said last named passages.

13. In a pneumatic player action, a wind chest having valve chambers at one side, valves in said chambers, a cap plate for one or more of said valves adapted to seat the same, but mounted independently of said valves, separate actuators for said valves serving to mount and guide the same, said actuators located wholly within said chest, a diaphragm board provided with diaphragms to operate said actuators, closing the chest at the side opposite the valves,

pneumatics beneath the chest having fixed upper leaves and movable lower leaves, and passages leading directly from the fixed upper leaves of the pneumatics through the 5 chest to the valve chambers.

14. In a pneumatic player action, a wind chest having a downwardly projecting extension, said chest provided at one side with a plurality of valve chambers, horizontally 10 movable valves in said valve chambers, separate actuators for said valves in said wind chest, a cap plate at one side of the chest provided with valve ports provided with diaphragms to operate the valves, a diaphragm 15 board at the other side of the chest co-operating with the actuators, said actuators constructed to have a certain amount of movement relatively to the corresponding valves but to support and guide the valves 20 independently of the cap plate, and pneumatics at the lower part of the chest communicating with the valve chambers by passages in said extension and in the chest.

15. In a pneumatic player action, a wind 25 chest having a plurality of valve chambers at one side, a cap plate applied to the last mentioned side of the chest, valves in said valve chambers mounted independently of the cap plate, actuators for said valves in 30 said chest mounted separately from the valves but adapted to support and guide the same, and a diaphragm board at the side of the chest opposite the cap plate provided with diaphragms to operate said actuators, 35 said actuators being removable from the chest when the diaphragm board is removed, and said valves being removable from the chest when the cap plate is removed.

16. In a pneumatic player action, a wind 40 chest having a downwardly projecting extension, a connecting rail in the angle between the extension and the main part of the chest, pneumatics applied to said connecting rail, horizontally movable valves in the 45 chest, horizontally movable actuators in the chest for operating said valves, a diaphragm board at one side of the chest provided with diaphragms for operating the actuators, a cap plate at the other side of the 50 chest provided with valve ports co-operating with the valves, and passages in the chest structure leading from the valves to said pneumatics.

17. In a pneumatic player action, a wind 55 chest having a downwardly projecting extension, a connecting rail in the angle between the extension and the main part of the chest, pneumatics applied to said connecting rail, horizontally movable valves in 60 the chest, horizontally movable actuators in the chest for operating said valves, a diaphragm board at one side of the chest provided with diaphragms for operating the actuators, a cap plate at the other side of 65 the chest provided with valve ports co-oper-

ating with the valves, and passages in the chest structure leading from the valves to said pneumatics, said actuators being removable from the chest independently of the valves.

18. In a pneumatic player action, a wind 70 chest, having a downwardly projecting extension, a connecting rail in the angle between the extension and the main part of the chest, pneumatics applied to said connecting rail, horizontally movable valves in the chest, horizontally movable actuators in the chest for operating said valves, a diaphragm board at one side of the chest provided with diaphragms for operating the 80 actuators, a cap plate at the other side of the chest provided with valve ports co-operating with the valves, and passages in the chest structure leading from the valves to said pneumatics, said valves being removable from the chest independently of the actuators when the cap plate is removed.

19. In a pneumatic player action, a wind 90 chest having a downwardly projecting extension, a connecting rail in the angle between the extension and the main part of the chest, pneumatics applied to said connecting rail, horizontally movable valves in the chest, horizontally movable actuators in the chest for operating said valves, a diaphragm board at one side of the chest provided with diaphragms for operating the 95 actuators, a cap plate at the other side of the chest provided with valve ports co-operating with the valves, and passages in the 100 chest structure leading from the valves to said pneumatics, said valves being removable from the chest independently of the actuators when the cap plate is removed, and said actuators being removable from the 105 chest independently of the valves when the diaphragm board is removed.

20. In a pneumatic player action, a wind 110 chest having a plurality of valve chambers at one side arranged in tiers, valves in said valve chambers, actuators for the valves in said chest, pneumatics arranged in tiers and secured to the lower part of the chest structure, said pneumatics having fixed upper leaves and removable lower leaves, the 115 larger ends of said pneumatics projecting beyond that side of the chest at which the actuators are located, a diaphragm board at the last named side of the chest mounted independently of the actuators, a cap plate 120 at the other side of the chest mounted independently of the valves, and passages independent of the cap plate connecting the pneumatics of the different tiers directly with the corresponding valve chambers.

21. In a pneumatic player action, a wind 125 chest having a plurality of valve chambers at one side communicating with the main tension chamber by ports, said chest having a shelf projecting rearwardly into the main 130

5 tension chamber substantially in line with said ports, a cap plate inclosing the valve chambers, valves in the valve chambers, valve actuators slidably mounted in said shelf and separate from the valves but supporting and guiding the valves loosely so that the latter are freely removable from the chest when the cap plate is removed, a diaphragm board cooperating with the 10 actuators, pneumatics, and passages connecting the pneumatics with the valve chambers.

22. In a pneumatic player action, a wind chest having a plurality of valve chambers at one side communicating with the main 15 tension chamber by ports, said chest having a shelf projecting rearwardly into the main tension chamber substantially in line with said ports, a cap plate inclosing the valve chambers, valves in the valve chambers, 20 valve actuators slidably mounted in said shelf and separate from the valves but supporting and guiding the valves loosely so that the latter are freely removable from the chest when the cap plate is removed, a diaphragm board provided with diaphragms 25 for operating the actuators, pneumatics, and passages connecting the pneumatics with the valve chambers, said passages extending through the chest independently of the cap 30 plate.

23. In a pneumatic player action, a wind chest having valve chambers at one side, horizontally movable valves in said valve chambers, valve bumpers in said chest having loose telescopic engagement with the valves, a cap plate at one side of the chest provided with valve ports coöperating with the valves, a diaphragm board at the opposite side of the chest having diaphragms for 35 operating said valve bumpers, pneumatics, and passages connecting the pneumatics through the chest structure with the valve chambers.

24. In a pneumatic player action, a wind 40 chest having a plurality of valve chambers bored therein at one side, valves in said valve chambers, valve bumpers in the wind chest having loose telescopic engagement with the corresponding valves, a shelf in 45 the chest for guiding the valve bumpers, a diaphragm board at one side of the chest having diaphragms for operating the valve bumpers, and means at the opposite side of the chest for closing the valve chambers, said valves being freely removable from the chest when said last named means is removed.

25. In a pneumatic player action, a wind 50 chest having a plurality of valve chambers bored therein at one side, valves in said valve chambers, valve bumpers in the wind chest having loose telescopic engagement with the corresponding valves, a shelf in 55 the chest for guiding the valve bumpers, a diaphragm board at one side of the chest

having diaphragms for operating the valve bumpers, and means at the opposite side of the chest for closing the valve chambers, said valves being freely removable from the chest when said last named means is removed, and said valve bumpers being removable from the chest independently of the valves when said diaphragm board is removed. 70

26. In a pneumatic player action, a valve 75 removable as a unit from the action on one side, and an actuating bumper for said valve removable as a unit from the player action on the other side, said valve and valve bumper having loose telescopic engagement 80 when assembled.

27. In a pneumatic player action, a chest block having a plurality of valve chambers at one side, movable valve bumpers having stems projecting into said chambers, and 85 valves in said chambers loosely engaging said stems but supported and guided thereby.

28. In a pneumatic player action, a chest block having a tension chamber at one side with a laterally extending shelf, a valve 90 bumper provided with a stem guided in said shelf and projecting toward the other side of the valve block, and a valve on such other side of the valve block having loose engagement with said stem but supported and 95 guided thereby.

29. In a pneumatic player action, a chest block having a tension chamber at one side and a plurality of valve chambers in the other side, said valve chambers adapted to 100 communicate with said tension chamber, a shelf in the tension chamber in line with the valve chamber, a valve bumper having a stem guided in said shelf, means for actuating said stem, and a valve in the valve chamber loosely engaging the bumper stem but supported and guided thereby and removable from the chest independently of said stem. 105

30. In a pneumatic player action, a chest 110 block having a plurality of valve chambers at one side, valves in said chambers, a removable cap plate for retaining said valves in said chambers, and valve actuators separate from said valves but supporting and 115 guiding the same, said valves being removable from said chest block when said cap plate is removed.

31. In a pneumatic player action, a chest 120 block, valves therein, movable actuators for said valves supporting and guiding the same, means for operating said actuators, and removable means for retaining said valves in said block, said valves being removable from the front of the block when said last-named 125 means is removed, independently of said valve actuators.

32. A pneumatic player action including a chest block having a plurality of valve chambers at one side, valves in said valve 130

- chambers, valve actuators separate from said valves, said valves being unattached to said actuators but resting freely thereon, and a removable cap plate for said valve chambers, said cap plate being the sole means for retaining the valves in said valve chambers.
33. In a pneumatic player action, a chest block having a plurality of removable valves, a removable cap plate section common to said valves having openings at the front of the chest controlled by said valves, and a muffler covering said cap plate.
34. In a pneumatic player action, a chest block having a plurality of horizontal valve chambers bored therein at one side, horizontally reciprocable valves in said valve chambers, a cap plate inclosing said valve chambers and having ports for said valves, said valves being mounted independently of said cap plate and being freely removable from the chest when the cap plate is removed, separate actuators in the chest for supporting and guiding said valves, and a diaphragm board provided with diaphragms for operating said actuators.
35. In a pneumatic player action, a chest block having a plurality of valve chambers at one side, movable valve bumpers having stems projecting into said chambers, and horizontally movable valves in said valve chambers having loose telescopic engagement with said stems whereby said valves are supported and guided wholly by said stems.
36. In a pneumatic player action, a chest block having a plurality of valve chambers therein at one side, valves in said chambers, a removable cap plate independent of the valves having ports adapted to be closed by said valves, and valve actuators separate from said valves, said valves being unattached either to said chambers or to said actuators and freely liftable out of said valve chambers when said cap plate is removed.
37. In a player piano, a block having valve chambers formed therein, valves in said chambers, a board having bores formed therein communicating with said chambers, said bores being spaced apart to conform to the spacing of a selected player action scale, a connecting rail having a lateral edge positioned to abut a face of said board, said rail having bores through said lateral edge positioned to communicate with said first mentioned bores and extending inwardly from said lateral edge at an angle to each other, whereby the inner ends of said last mentioned bores are spaced apart to conform to scales other than said selected player action scale.
38. In a player piano, a board having bores formed therein, a connecting rail having a lateral edge positioned to abut a face of said board, said rail having bores through said lateral edge positioned to communicate with said first mentioned bores and extending inwardly from said lateral edge at an angle to each other.
39. In a player piano, a pneumatic supporting rail having a beveled lateral face, pneumatics rigidly mounted upon said beveled face, said rail having passages communicating with said pneumatics, comprising bores extending inwardly from a lateral edge of said rail in the same plane but at angles to each other.
40. In a player piano, a pneumatic supporting rail, pneumatics mounted upon said rail, said rail having passages communicating with said pneumatics, comprising bores extending inwardly through a lateral edge of said rail and lying in the same plane but at angles to each other.
41. A pneumatic player action including a wind chest, horizontally movable valves therein, said wind chest having a downwardly projecting extension provided with passages, striker pneumatics supported by said extension, said passages communicating with said pneumatics and controlled by said valves.
42. In a player piano, a board having bores formed therein, said bores being spaced apart to conform to a selected player action scale, a rail, associated with said board, having bores formed through an edge thereof to communicate with said first mentioned bores, and extending inwardly from the edge at an angle to each other, whereby the inner ends of said last mentioned bores are spaced apart to conform to scales other than said selected scale.
- In witness whereof, I have hereunto set my hand on the 9 day of April, 1918.

STANLEY L. FISHER.
